Primary Examiner — R. Johnson(57) **CLAIM**

The ornamental design for a synthesizer as shown and described.

DESCRIPTION

1. Synthesizer
- 1.1 : Perspective
- 1.2 : Perspective
- 1.3 : Front
- 1.4 : Back
- 1.5 : Left
- 1.6 : Right
- 1.7 : Top
- 1.8 : Bottom
- 1.9 : Enlarged
- 1.10 : Enlarged
- 1.11 : Exploded

The broken lines in the reproductions depict portions of the synthesizer that form no part of the claimed design; figs. 1.9 and 1.10 are the enlarged views of the portion taken at line 1.9, 1.10 in fig. 1.1; the dash dot dash broken lines in the reproductions represent boundaries for the enlarged views and form no part of the claimed design; the explanatory curved bracket in fig. 1.11 shows the association of elements and forms no part of the claimed design.

1 Claim, 11 Drawing Sheets(56)
